Primary Examiner — Karen E Eldridge Powers

(57) **CLAIM**

I claim the ornamental design for an paint brush with angled handle and without a ferrule, as shown and described.

DESCRIPTION

FIG. 1 is a front elevation view of an paint brush with angled handle and without a ferrule showing my new design.

FIG. 2 is a right side elevation view thereof; and,

FIG. 3 is a perspective view thereof.

1 Claim, 2 Drawing Sheets
